UNITED STATES PATENT OFFICE.

JANE H. BURNS AND JOHN ANDERSON, OF MIDDLETOWN, CONNECTICUT.

THREAD HOLDER AND CUTTER.

Application filed July 20, 1921. Serial No. 486,199.

To all whom it may concern:

Be it known that we, JANE H. BURNS and JOHN ANDERSON, both citizens of the United States, and residents of Middletown, in the 5 county of Middlesex and State of Connecticut, have invented a new and Improved Thread Holder and Cutter, of which the following is a full, clear, and exact description.

10 This invention relates to a thread holder and cutter for use in conjunction with spools.

After a spool of thread has been opened and a portion of the thread unwound there 15 is no means for fixing the end of the thread and when the spool is thrown into a basket or other container the thread unwinds and becomes entangled with the other spools or other articles.

20 The object of this invention is to provide a device that may be attached to spools, which holds the end of the thread and which has in conjunction therewith means for cutting the thread.

25 This object is accomplished by clamping two disk members together and providing in conjunction with the clamping means spring means for attaching the disk members to the spool. A thread cutting means 30 is provided in conjunction with one of the disks.

This and other objects of the invention will be more clearly understood from the following detailed description and accompanying drawings.

35 Figure 1 is a top plan view of the thread cutter and holder;

Figure 2 is a cross section along the line 2—2, Figure 1;

40 Figure 3 is a cross section along the line 3—3, Figure 2;

Figure 4 is a cross section along the line 4—4, Figure 2;

45 Figure 5 is a cross section through the thread holder and cutter showing a modification of the spring means used for attaching it to the spool; and

Figure 6 is a cross section along the line 6—6, Figure 5.

50 Referring to the above-mentioned drawings, the spool 10 has thread 11 wound thereon. An opening 12, which extends from end to end of the spool 10, is provided. The thread holder consists of two disks 13 and 14 which have openings 15 and 16

through their centers. The lower disk is flat and has a portion of the edge bent up forming a blade 17. This blade is sharpened, presenting a knife edge 18 which serves for cutting the thread. The upper 60 disk is curved to the shape of a saucer and is mounted on the disk 17 with the concave side upward so that the opening 15 coincides with the opening 16. A piece of sheet metal 19 is folded to a cylindrical shape 65 about the size of the cylindrical opening 12 in the spool, and a plurality of tongues 20 are cut in its upper end. Every second one of these tongues 20 are bent outwards forming shoulders. The remaining tongues are 70 projected through the openings in the disks 13 and 14 until the shoulders come in contact with the disk 14. Thus the tongues extending through the openings are bent over 75 into contact with the disk 13 thus clamping 75 the disks together. The bottom portion of the sheet of metal is cut forming long tongues 21 which are bent outward. These tongues form spring means for detaching the thread holder and cutter to the spool. Integral 80 with the disk 14 is a projection 22.

A modification of the spring means for connecting the thread cutter and holder to the spool is shown in Figure 5. In this case the sheet of metal 19 is rolled into a cylindrical form with a space between its edges. The upper end is cut in tongues as already described and attached to the disk members. In attaching it to the disk members, the upper end is pressed inward, making it of a 90 slightly smaller diameter than the lower end. In order to insert the lower end into the spool the sides have to be pressed together and they tend to return to their normal position and thus provide a spring 95 means for connecting the device to the spool.

Many other modifications of the spring means for connecting the thread holder and cutter to the spool may be made.

The operation of this device is as follows:

The spring means are pressed together and inserted in the opening 12 in the spool. The device is then pushed home until the disk 14 comes in contact with the end of the 105 spool. After the desired amount of thread has been unwound from the spool the thread is brought into contact with the projection 22 and drawn between the disks 13 and 14 and then it is cut off by means of the cutter 110

17. It will be seen that the end of the thread will remain between the disks 13 and 14.

Claim.

5 A thread holder and cutter for use with spools, comprising a flat disk, perforated at its centre, said disk having a projection extending outward from one side and an upturned portion on the opposite side form-

ing a cutter, a hollow cylindrical spring member provided with means on its upper end for clamping the disks together, and spring members on its lower end for engaging the spool to retain the thread holder and cutter in position on the same.

JANE H. BURNS.
JOHN ANDERSON.
